UNITED STATES PATENT OFFICE

THOMAS J. ARBRON, OF DETROIT, MICHIGAN, ASSIGNOR TO ROTO PUMP COMPANY, OF DETROIT, MICHIGAN, A CORPORATION OF MICHIGAN

DESIGN FOR A HAIR DRYING CABINET

Application filed December 21, 1931. Serial No. 42,271. Term of patent 7 years.

To all whom it may concern:

Be it known that I, THOMAS J. ARBRON, a citizen of the United States, residing at Detroit, in the county of Wayne and State of Michigan, have invented a new, original, and ornamental Design for a Hair Drying Cabinet, of which the following is a specification, reference being had to the accompanying drawing, forming part thereof.

The figure is a perspective view of a hair drying cabinet showing my new design.

I claim:

The ornamental design for a hair drying cabinet, as shown.

THOMAS J. ARBRON.
